UNITED STATES PATENT OFFICE.

CARL S. MAGON AND WILLIAM W. WINCHESTER, OF PHILADELPHIA, PENNSYLVANIA,
ASSIGNORS TO GILLINDER & SONS, INC., OF PHILADELPHIA, PENNSYLVANIA, A
CORPORATION OF PENNSYLVANIA.

DESIGN FOR DECORATIVE SHEET-GLASS.

40,794.

Specification for Design. Patented July 26, 1910.

Application filed June 11, 1909. Serial No. 501,667. Term of patent 14 years.

To all whom it may concern:

Be it known that we, CARL S. MAGON and WILLIAM W. WINCHESTER, citizens of the United States, and residents of the city and county of Philadelphia and State of Pennsylvania, have invented a new, original, and ornamental Design for Decorative Sheet-Glass, of which the following is a specification, reference being had to the accompanying drawing, forming part thereof.

The figure is a plan view of a sheet of glass showing our new design.

The design is formed upon clear or transparent glass, the grapes A, indicated by sur-

face line shading, being cut or pressed; the leaves and stems B, indicated by parallel diagonal cross lines, being etched; and the background C, indicated by stippling, being roughed and semiopaque.

We claim—

The ornamental design for decorative sheet glass, as shown and described.

CARL S. MAGON.
WM. W. WINCHESTER.
